BINDING CONSTRUCTION AND METHOD

Walter Grumbacher, New York, N. Y., assignor
to Spiral Binding Co. Inc., New York, N. Y., a
corporation of New York

Application March 1, 1935, Serial No. 8,795

15 Claims. (Cl. 281—25)

This invention relates to the binding of stacks of sheeted material, and in particular to a binding in which a continuous binding element is used, and in one of its aspects to a binding in which a continuous spiral element is used. Coordinate-
ly therewith it relates to the method for utilizing such continuous spiral elements.

One of the types of binding for stacks of sheet-
ed material comprises a stack having perforations
10 applied along one edge of the stack, and a con-
tinuous helical or spiral wire is threaded through
the perforations. Such a binding construction,
while it has many advantages, also has disadvan-
tages in that the sheets, as they turn around the
15 spiral, when the stack is opened, move laterally
at the same time, because of the pitch of the
spiral, and, in addition, the contact between the
coils of the spiral and the walls of the perfora-
tions is apt, because of the pitch of the spiral
20 coils, to result in binding and the distortion of
the spiral which causes it either to twist or
untwist.

It has been proposed to eliminate the first of
these disadvantages by deforming the coils of
25 the spiral into ring-like members having no pitch
and using other portions of the deformed spiral
to connect these ring-like members. While this
serves to overcome the objectionable feature of
30 lateral movement it still does not prevent dis-
tortion of the binding member, because there is
still a certain amount of binding action between
the coils of the binding element and the walls
of the perforations.

It is among the objects of my invention to pre-
35 vent the distortion and binding incident to the
use of the ordinary spiral binding element, and
also to utilize the spirally coiled binding element
in the formation of a continuous binding element
40 that will have no pitch and will be free from
distortion.

For the attainment of these objects and such
other objects as will hereinafter appear or be
pointed out, I have illustrated several embodi-
45 ments of my invention in the drawings, in which:

Figure 1 is a view in perspective of one embodi-
ment of my invention;

Figure 2 is an end elevation of another embodi-
ment of my invention utilizing a connecting ele-
ment similar to the one shown in Figure 1;

Figure 3 is a plan view of the embodiment
50 shown in Figure 2;

Figures 4 and 5 are an end elevation and a
plan view respectively of one stage in the manu-
facture of the construction shown in Figures 2
55 and 3;

Figure 6 is an end elevation intended to illus-
trate another stage in the formation of the con-
struction of Figures 2 and 3;

Figure 7 is an end elevation illustrating a fur-
ther stage in the manufacture of the construc-
5 tion of Figures 2 and 3;

Figure 8 is an end elevation of another form
of my invention, resembling that shown in Fig-
ures 2 and 3;

Figure 9 is a further modification of my inven-
10 tion in many ways similar to the showings of
Figures 2 and 3;

Figure 10 illustrates another embodiment of
my invention;

Figure 11 illustrates still another embodiment
15 of my invention;

Figures 12 and 13 illustrate a further embodi-
ment of my invention, Figure 12 showing parts
thereof before assembly, and Figure 13 being the
assembled construction; and

Figures 14, 15 and 16 illustrate still other em-
bodiments of my invention.

Referring now to the drawings in detail it will
be observed that in Figure 1 I have shown a
continuous binding element 20 consisting of a
25 ring-shaped members 22 transversely disposed to the
axis of the binding element, and each ring con-
nected to the adjacent rings 22 by longitudinally
disposed connecting members 24. The members
24 are shown as fastened by any suitable fasten-
30 ing means, such as staples 32, to a securing mem-
ber 26 of any suitable form, and which may be a
cover used for the stack of sheets which is indi-
cated by dotted lines at 28, and is provided with
perforations 30 through which the members 22
35 pass. It will be observed that if the members 24
were left free they might be twisted out of their
normal position of longitudinal alignment into
some such position as is indicated by the dotted
line A. However, by fastening them to a rela-
40 tively rigid member 26, such twisting is prevented,
and the members 24 are kept in longitudinal
alignment under all ordinary conditions of use.
It will further be observed that by this construc-
45 tion the objects heretofore mentioned, namely
the prevention of lateral movement of the sheets
of the stack and the prevention of twisting of
the stack, are attained.

In Figure 2 is shown a modified construction
in which a continuous binding element 40 is
50 similar in type to the element 20 of Figure 1,
and has transversely disposed ring-like members
42 passing through perforations 50 of the stack
48, and longitudinally disposed members 44 con-
necting the rings 42. The member 46 is doubled
55

over so as to enclose the members 44 between its doubled-over portions, and the doubled-over portions are fastened together by any suitable fastening means, such as cement, or the staples 52. 5 Perforations 47 are provided in the doubled-over portions of the member 46, and the rings 42 pass therethrough.

Figures 4, 5, 6 and 7 are intended to illustrate various stages in one manner of assembling the 10 construction of Figures 2 and 3. I have found it very convenient to start by laying the stack 48 on the member 46 before the end portion of the latter is doubled over, and while it is in flattened form, and with its inner row of perforations 15 aligning with the stack, and then to thread the spiral element 42 through the perforations both of the stack and of the member 46. By referring to Figure 4 it will be observed that the spiral element 42a passes through both sets of perforations 47 of the member 46. It will be understood 20 that the two rows of perforations 47 must be dimensioned and positioned in such a way, that they will permit passage of the spiral element 42a during the threading operation and yet will be 25 adapted for the passage of rings 42 when the member 46 is doubled over.

The next stage is shown in Figure 6, and comprises positioning the member 46 in some manner such as shown in Figure 6, and distorting the 30 spiral element 42a so as to form the ring members 42 and the longitudinal members 44. It will be observed that the deformation of the spiral takes place in such a way that the longitudinal members 44 and the stack 48 are located on opposite 35 sides of the members 46.

Thereafter the member 46 may be doubled over at such a point that the two rows of perforations are superposed, the respective perforations being in sufficiently registered alignment as to 40 permit passage therethrough of the rings 42. This stage is indicated in Figure 7.

The final stage is that shown in Figure 2; as there shown the staples 52 have been applied so as to fasten the bent over portions of member 46 in place. Obviously any suitable way of fastening, such as cementing, may be used with equal 45 effect.

In the modification of Figure 8, the stack 68 has a binder 60 of the same type as the binder 20 of Figure 1, with the ring 62 thereof passing 50 through the perforations 70 of the stack. This binder comprises also longitudinally disposed connecting members 64 uniting adjacent rings 62. The member 66 corresponds to the member 46 of Figure 2 and comprises doubled over portions shown as united by staples 72 so as to prevent 55 their spreading after they are placed so as to enclose the longitudinal members 64. The member 66 may be applied to the stack in the same manner as the member 46 of Figures 2 and 3, as has just been described in connection with Figures 5 to 7. It will be observed that the member 66 is shown as symmetrical in construction with laterally extending wings of equal length. I 60 have found this form very convenient for purposes of attaching the stack to a cover. For instance, where the member 66 is made rigid the wings thereof may be slid into a channel carried by the cover, or the wings may be fastened to the cover by any other similar method, either by riveting or by cementing. Where the member is not rigid the wings may well be fastened to the cover by cementing, sewing or other suitable ways. In all of these constructions the doubled 65 over portion may assume an upstanding position

in relation to the cover, which upstanding construction is found to be very useful.

Of all the possible variations of this construction I may mention one in which one of the wings 66 is omitted and with it the doubled over portion. Members 64 might be fastened with staples as in Figure 1. Instead of a flat member, as 26 in Figure 1, however, the binder passes through perforations in a portion upstanding from the back. 10

In Figure 9 the stack 88 is held together by the binding element 80, which is of the type of element 20 of Figure 1, and comprises ring like members 82 and longitudinal members 84. The aligning member 86 for the longitudinal members 15 84 comprises two separate pieces, 94 and 96, provided respectively with perforations 98 and 100 and joined by suitable means such as staples 102, shown as disposed in two rows on opposite sides of the member 84, although it will be obvious that 20 they may be disposed in many other ways. To assemble the construction of Figure 9 it is only necessary to place the members 94 and 96 on the stack 88, with their perforations in alignment with the perforations of the stack, and to thread 25 a spiral binding element therethrough, which is then deformed as has been explained in connection with Figures 2 to 7 so as to comprise ring portions 82 passing through the perforations 98 and 100 and through the perforations of the 30 stack, and longitudinal bars 84, the latter being positioned between the members 94 and 96.

In Figure 10 I have shown a construction in which the binder 110, comprising as before, ring-like portions 112 and longitudinal bars 104, is 35 threaded through a stack 108, and the bars 104 are longitudinally aligned by a relatively rigid member 106 comprising two portions 114 and 116, suitably united, as by staples 122. Instead of perforations as in the forms heretofore described 40 the parts 114 and 116 are provided with open slots 120 that register with each other and with the perforations of the stack. In assembling this construction the following procedure may be used. First the member 110 is threaded into the 45 stack while in helical form. It is then deformed so as to form the longitudinal bars 104. The member 106 is then applied by passing its slots 120 over the rings 112 and placing the staples 124 across the slots so as to prevent withdrawal of 50 the rings. Staples 122 are shown as uniting the two parts of member 106, and these may be applied before or after assembly of member 106 with the stack. It will be understood that many other arrangements for fastening might be used, 55 those shown being by way of illustration merely.

In Figure 11 I have indicated an aligning member 140 provided with slots 142 of the bayonet type. These slots comprise inwardly extending portions 144, and portions 146 extending at right 60 angles thereto, and are adapted for the reception of the ring members 152 of a binding element 150 of the type heretofore disclosed in Figure 1, and which is indicated in dotted lines for the sake of clearness. The longitudinal members 154 of element 150 overlie the aligning member 140, and are fastened thereto by some suitable means, such as staples 148, which confine the rings 152 to the inner portions of the slots 142, as clearly appears from the drawings.

In Figures 12 and 13 the member 166, similar to the member 140 of Figure 11, comprises portions 164 and 168 provided with bayonet slots 162 similar to those described in Figure 11, and the two members are intended for superposition. The 70 75

ring members 172 of a binding element 170 may be inserted into the slots of the two members 164, and 168 and they are then superposed so that the longitudinal bars 174 connecting the rings 172 of the binding element 170, are positioned between the members 164 and 168. On sliding 164 and 168 relatively to each other the inwardly extending portions of the respective slots 162 thereof are disposed in aligned relation, and the ring members 172 are held in the inner portions of the slots, as shown in Figure 13. On applying suitable fastening means, such as staples 176, to unite 164 and 168, such locking becomes permanent. It is obvious that instead of both members 164 and 166 being provided with bayonet slots only one member may have the bayonet slots and the other member may be provided with slots of any other desired type. Also, that instead of bayonet slots being used, the slots may have a great variety of 20 conformations.

In Figure 14 I have shown diagrammatically, a binding element 160 provided, as before, with ring portions 182, and longitudinal bars 184, and the alignment of bars 184 is indicated as being effected by a bar 186, shown in dotted lines for purposes of clarity, and intended to be permanently fastened to the bars 184, such as by spot-welding. It will be understood of course that if the binding element is initially of spiral form, the 30 stack is positioned on the binding element before the formation of bars 184, and before the welding.

Figure 15 shows a member 200 provided with slots 198 and doubled over the longitudinal bars 194 of a binding element 190 so as to clamp them 35 and hold them in alignment. The binding element 190, similar to element 20 of Figure 1, comprises the ring members 192 united by the bars 194 heretofore mentioned.

A modification of the idea of Figure 15 is shown 40 in Figure 16, in which the aligning element 210 comprises portions 204 and 206 united by fastening means, such as screws 208. The binding element is denoted by 220 and comprises rings 222 and the longitudinal connecting bars 224. The 45 member 206 may be provided with a channel adapted to receive the bars 224, and to clamp them in aligned position.

While I have described the longitudinal bars of the binding elements as longitudinally aligned, it 50 is to be understood that such alignment is not necessary for the purposes of my invention, but is merely a convenient and obvious embodiment thereof. For instance, the longitudinal bars might be held fixed in a position in which they are laterally, or circumferentially spaced from each 55 other, but they must be prevented from lateral displacement from such position.

It will be understood that the embodiments of 60 my invention herein disclosed are by way of illustration only, and that my invention may be embodied in many other forms, as will be obvious to those skilled in the art, without departing from the spirit thereof, as defined in the appended claims.

Having thus described my invention and illustrated its use, what I now claim as new and seek to secure by Letters Patent, is:

1. In the method of binding together a stack of sheet material, the sheets of which are provided 65 with registering perforations, the steps of superposing a relatively rigid member provided with two parallel rows of perforations on the stack, with the perforations of one of said rows aligning with those of the stack, threading a continuous 70 spiral element through the two rows of perfora-

tions of the relatively rigid member and the perforations of the stack, deforming said spiral element so that it is constituted by transversely disposed ring-like members joined by longitudinally disposed elements, and so that said rigid member is disposed between the stack and said elements, doubling over said rigid member so as to bring portions of the perforations of the said two rows of perforations thereof into registration and so as to include therewithin said longitudinal elements, 10 and securing together said doubled over portions so as to lock said elements permanently therewithin. 5

2. In the method of binding together a stack of sheet material, the sheets of which are provided 15 with registering perforations, the steps of superposing a relatively rigid member provided with two parallel rows of perforations on the stack, with the perforations of one of said rows aligning with those of the stack, threading a continuous 20 spiral element through the two rows of perforations of the relatively rigid member and the perforations of the stack, deforming said spiral element so that it is constituted by transversely disposed ring-like members joined by longitudinally disposed elements, and so that said rigid member is disposed between the stack and said elements, doubling over said rigid member so as to bring portions of the perforations of the 25 said two rows of perforations thereof into registration and so as to include therewithin said longitudinal elements. 30

3. In combination, a stack of perforated sheets 35 united by a continuous binding element comprising transversely disposed loops each connected to the adjacent loops by longitudinally extending elements, and means for preventing displacement of said elements from their position of longitudinal alignment said means comprising a relatively rigid member having an extension 40 thereof angularly disposed in relation thereto and adapted for associating said member with extraneous devices, and fastening means uniting said elements and said relatively rigid member so as to prevent separation thereof. 45

4. In combination with a stock of sheets having 50 perforations therein, a continuous elongated binding element comprising transversely disposed annular members serially connected by longitudinally disposed elements, and means to hold said elements in longitudinal alignment, said means comprising a relatively rigid member having perforations 55 therein aligning with the perforations of the stack, said annular members passing through said perforations, said rigid member engaging said elements on opposed sides thereof, and fastening means for holding said elements in fixed relation to said rigid member. 60

5. In combination with a stack of sheets, a continuous elongated binding element comprising 65 transversely disposed annular members serially connected by longitudinally disposed elements, and means to hold said elements in longitudinal alignment, said means comprising a pair of substantially rigid members connected together so as to include said elements therebetween. 70

6. In combination with a stack of sheets having 75 perforations along one edge thereof, a continuous elongated binding element comprising transversely disposed ring-like members passing through said perforations and serially connected by longitudinally disposed elements, and means to hold said elements against lateral displacement, said means comprising a relatively rigid member having one portion thereof doubled over 75

another portion, and secured together so as to include said elements therebetween.

7. A book consisting of a plurality of leaves; a continuous wire binding for said leaves consisting of a plurality of substantially parallel loops each terminating in a straight portion which is in a plane substantially at right angles to the plane of the said loops; a backer carried by said binding and consisting of a strip having a plurality of loop-receiving slots formed therein the said slots also serving to define and form tongues on said backer which contact with the said straight portions; and means for closing the said slots.

8. A book consisting of a plurality of leaves; a continuous wire binding for said leaves consisting of a plurality of substantially parallel loops each terminating in a straight portion which is in a plane substantially at right angles to the planes of the said loops; a backer carried by said binding and consisting of a strip adapted to contact with said straight portions and having a plurality of loop-receiving slots formed therein; and means for closing the said slots.

9. A book consisting of a plurality of leaves, a continuous wire binding for said leaves consisting of a plurality of substantially parallel loops united by portions disposed in a plane substantially at right angles to the planes of the said loops; a backer carried by said binding and consisting of a strip having a plurality of loop-receiving slots formed therein, the said slots also serving to define and form tongues on said backer which contact with the said straight portions; and means for closing the said slots.

10. A book consisting of a plurality of leaves, a continuous wire binding for said leaves consisting of a plurality of substantially parallel loops united by portions disposed in a plane substantially at right angles to the planes of the said loops; a backer carried by said binding and consisting of a strip having a plurality of loop-receiving slots formed therein, adapted to contact with said aforementioned portions of the binding; and means for closing the said slots.

11. A book consisting of a plurality of leaves, a continuous wire binding for said leaves consisting of a plurality of substantially parallel loops united by portions disposed in a plane substantially at right angles to the planes of the said loops; a backer carried by said binding and consisting of a strip adapted to contact with said straight portions and having a plurality of loop-receiving slots formed in the edge portions of the backer; and means for closing the said slots.

12. In the method of binding together a stack of sheet material, the sheets of which are provided with registering perforations, the steps of superposing a relatively rigid member provided with two parallel rows of perforations on the stack, with the perforations of one of said rows aligning with those of the stack, threading a continuous spiral element through the two rows of perforations of the relatively rigid member and the perforations of the stack, deforming said spiral element so that it is constituted by transversely disposed ring-like members joined by longitudinally disposed elements, and so that

said rigid member is disposed between the stack and said elements, doubling over said rigid member so as to bring the perforations of the said two rows of perforations thereof into registration and so as to include therewithin said longitudinal elements, and securing together said doubled over portion so as to lock said elements permanently therewithin.

13. In the method of binding together a stack of sheet material, the sheets of which are provided with registering perforations, the steps of superposing a relatively rigid member provided with two parallel rows of perforations on the stack, with the perforations of one of said rows aligning with those of the stack, threading a continuous spiral element through the two rows of perforations of the relatively rigid member and the perforations of the stack, deforming said spiral element so that it is constituted by transversely disposed ring-like members joined by longitudinally disposed elements, and so that said rigid member is disposed between the stack and said elements, doubling over said rigid member so as to bring the perforations of the said two rows of perforations thereof into registration and so as to include therewithin said longitudinal elements.

14. In the method of binding together a stack of sheet material, the sheets of which are provided with registering perforations, the steps of superposing a relatively rigid member provided with two parallel rows of perforations on the stack, with the perforations of one of said rows aligning with those of the stack, threading a continuous spiral element through the two rows of perforations of the relatively rigid member and the perforations of the stack, deforming said spiral element so that it is constituted by transversely disposed ring-like members joined by longitudinally disposed elements, and so that said rigid member is disposed between the stack and said elements, doubling over said rigid member so as to bring portions of the perforations of the said two rows of perforations thereof into overlapping relation and so as to include therewithin said doubled over portions so as to lock said elements permanently therewithin.

15. In the method of binding together a stack of sheet material, the sheets of which are provided with registering perforations, the steps of superposing a relatively rigid member provided with two parallel rows of perforations on the stack, with the perforations of one of said rows aligning with those of the stack, threading a continuous spiral element through the two rows of perforations of the relatively rigid member and the perforations of the stack, deforming said spiral element so that it is constituted by transversely disposed ring-like members joined by longitudinally disposed elements, and so that said rigid member is disposed between the stack and said elements, doubling over said rigid member so as to bring portions of the perforations of the said two rows of perforations thereof into overlapping relation and so as to include therewithin said longitudinal elements.

WALTER GRUMBACHER.
